(No Model.)

C. C. MILLER.
WINDOW SASH.

No. 554,075.

Patented Feb. 4, 1896.

UNITED STATES PATENT OFFICE.

CHARLES C. MILLER, OF BROOKLYN, NEW YORK.

WINDOW-SASH.

SPECIFICATION forming part of Letters Patent No. 554,075, dated February 4, 1896.

Application filed October 2, 1895. Serial No. 564,421. (No model.)

To all whom it may concern:

Be it known that I, CHARLES C. MILLER, of Brooklyn, in the county of Kings and State of New York, have invented a new and Improved 5 Window-Sash, of which the following is a full, clear, and exact description.

This invention relates to window-sash.

A window-sash as ordinarily constructed and arranged within a casing is apt to shrink 10 or swell with the atmospheric changes. When the sash is contracted it will rattle in the casing, and when expanded it is difficult to raise.

The object of my invention is to obviate these objections.

15 My invention consists in providing a yielding attachment for the side rail or rails of a sash, and to which the weight-cord is attached.

20 The invention further consists in the construction and novel arrangement of parts, as will hereinafter appear and be particularly pointed out in the appended claims.

25 Reference is to be had to the accompanying drawings, forming a part of this specification, in which similar characters of reference indicate corresponding parts in all the views.

30 Figure 1 is a front elevation of a sash embodying my invention. Fig. 2 is a section on the line 2 2 of Fig. 1. Fig. 3 is a longitudinal section of a yielding attachment. Fig. 4 is a front view of a portion thereof, and Fig. 5 is an end view.

35 Referring to the drawings, A designates the lower sash, A' the upper sash, and A² the window-casing. I have here shown a yielding attachment for each side rail of the sash; but it is to be understood that practically the same result will be attained by attaching it to one side rail only. The yielding attachment 40 comprises a metal boxing B, open at its front and adapted to slide between the stop-bead a and parting-bead a' of the casing. A metal shell B' is secured to the side rail of the sash by means of screws. This shell B' is 45 designed to fit snugly, yet movably, within the boxing B. As a means to provide a good hold for the screws employed for securing the shell to the sash-rail, I employ a metal rein-

force-strip b, placed within the shell and having tapped holes in which the screws engage. 50

Springs B² are attached to the reinforce-strip b, and their free ends bear against the inner surface of the boxing B, as shown in the drawings. I have here shown three springs; but more or less may be employed 55 without departing from the spirit of my invention. A guide pin or screw b' projects from the lower end wall of the shell through a guide-slot b² in the lower end wall of the boxing, and a sash-cord b³ is attached to the upper end wall of the shell and extends through a slot-opening b⁴ in the upper end wall of the boxing, over a pulley which is here shown as located on top of the casing A².

It will be observed that the shells B' for a 60 sash extend slightly beyond the surface of the stop-bead and parting-bead, and that the central fastening-screws a² serve as pivots on which the sash may be turned after removing the other screws, thus making it convenient 65 to clean the outer side of a glass by a person standing within a room.

70 By the construction shown and described it is clear that a sash may be easily removed, when desired, without first removing a stop-bead, as is necessary with sash of the ordinary construction.

Having thus described my invention, I 75 claim as new and desire to secure by Letters Patent—

80 1. The combination with a window-sash, of a yielding extension for a side rail thereof, comprising a metal boxing open at its front and adapted to slide in a window-casing, a metal shell secured to the side rail of the sash, a reinforce-strip in the shell, springs secured 85 to said reinforce-strip and bearing against the inner surface of the boxing, a pin extended from the lower end of the shell through a slot in the lower end of the boxing and the 90 said shell having an opening in its upper end wall for the passage of a sash-cord, substantially as specified.

95 2. The combination with a window-sash, of yielding extensions for the side rails thereof, comprising a metal boxing adapted to slide

in the window-casing, metal shells secured to the side rails of the sash and having their side portions extending into the boxings, the said shells being extended toward the center of the window slightly beyond the stop and parting beads of a casing whereby the sash may be turned on central horizontal pivotal connections with the shells, reinforce-strips in the

shells, springs secured to the reinforce-strips and bearing against the boxings, and a guide-¹⁰ pin at the lower end of the shells, substantially as specified.

CHARLES C. MILLER.
